CARBURETOR

Jay S. Culp, Detroit, Mich., assignor to Monarch Governor Company, Detroit, Mich., a corporation of Michigan

Application July 30, 1932, Serial No. 626,638

15 Claims. (Cl. 261—51)

This invention relates to carburetors for internal combustion engines, an object of the invention being to provide an improved device of this character which will be more efficient and effective in operation, relatively simple in construction and, therefore, more economical to manufacture, and which will be more adaptable to various kinds of engines while permitting better control or governing of the fuel mixture in accordance with engine requirements.

10 A further object of the invention is to provide a carburetor or fuel mixture governing device in which the throttle valve movement is controlled as a result of variations in pressure in the intake passage, and wherein the fuel is metered in an improved manner so as to effect a fuel supply varying in accordance with the engine requirements.

15 A further object is to provide a suction responsive throttle valve adapted to control the inflow of fuel into the mixing chamber or, more specifically, adapted to control by its movement a metering means for the fuel, yet in which the fuel supply is controlled at different speeds independently of the engine suction or throttle valve movement.

20 Another object of the invention is to provide a carburetor or fuel mixture governor having a streamlined throttle valve working in cooperation with a venturi in the intake; also to provide a throttle valve working in cooperation with a fuel nozzle whereby at idling speed when the throttle is closed the engine suction will open a fuel and air conduit past the throttle, and in which the fuel nozzle will be closed when the engine is not operating.

25 A further object of the invention is to provide a carburetor preferably of the down draft kind, having a suction actuated throttle valve located preferably in a Venturi passage and carrying a variable speed metering pin cooperating with a fuel nozzle, and in which the metering pin has a movement corresponding to the throttle valve movement and also has at predetermined times a movement independently thereof. Another object is to provide improved means whereby the fuel nozzle may be adjusted relative to the metering pin to enrich the mixture, and in which the position of the throttle valve itself may be adjusted.

30 Other objects of this invention will appear in the following description and appended claims, reference being had to the accompanying drawings forming a part of this specification where-

in like reference characters designate corresponding parts in the several views.

Fig. 1 is a vertical section illustrating one form of device embodying the invention.

Fig. 2 is a right hand side elevation of the structure of Fig. 1, the hood being shown in section.

Fig. 3 is a fragmentary left hand side elevation of the structure of Fig. 1, the hood being in section.

Fig. 4 is in part an enlarged section through lines 4—4 of Fig. 1.

Fig. 5 is a vertical section illustrating another form of device embodying the invention.

Fig. 6 is a right hand side elevation of the structure of Fig. 5, the hood being in section.

Fig. 7 is a section through lines 7—7 of Fig. 5.

Fig. 8 is an enlarged view of the metering pin.

Fig. 9 illustrates graphically a power curve produced in the use of the metering pin constructed substantially in accordance with Fig. 8.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

Referring to Figures 1 to 4 inclusive the carburetor is provided with a tubular conduit member 10 adapted to be bolted to an intake portion 11 of the engine manifold, and provided in its length with a Venturi portion 12 having its maximum constriction at 13. The tube 10 forms a guide for a slideable sleeve 14, and adjacent the upper end of the device the parts 10 and 14 are cut away at opposite sides at 15 to provide air passages. Mounted on the upper end of the sleeve 14 and centered by an extension 16 of the sleeve is a hood or canopy 17, the parts being clamped together by a knurled nut 18 threaded onto the portion 16.

The hood 17 not only provides an enclosure for the device but also acts as an air cleaner since the air enters at the lower open end of the hood, travels upwardly, then passes at right angles through the apertures 15 and thence downwardly. A return bent air stream is produced. The relatively lower velocity of the air entering the lower end of the hood as compared with the high velocity of the air after the air stream is

bent, permits heavier than air dirt particles to gravitate out of the air stream before entering the mixing chamber.

The sleeve 14 in the present instance has a 5 downwardly extending tubular portion 19 tapped at its lower end to receive the screw threaded stem 29 of a fuel nozzle 21. The stem has a longitudinal bore leading to a metering passage 21a cooperating with the metering pin, later 10 scribed, and thence terminating in an enlarged orifice 21b. The fuel preferably enters the tube 19 through a passage in a plug 22 which has an exteriorly tapered portion over which extends the expanded end of a flexible fuel pipe 23, the 15 parts being clamped by a nut 24, as illustrated in Fig. 4.

Mounted within the Venturi portion 12 of the tube 10 is a throttle valve 25 which, in the present preferred embodiment of the invention, is 20 in the form of a plunger. The head of this plunger is annular and is adapted to fit into the neck or constriction 13 of the venturi so as to close the passage, in the manner illustrated in Figure 1. The throttle valve or plunger 25 is 25 provided with radially extending guide wings 26 slidingly engaging the wall of the tube 19, thereby centering the valve in the passage throughout its movement between open and closed positions. It will be noted that the head of the plunger 30 which receives the impact of the inflowing air is tapered off from its center point beneath the fuel orifice 21b. Moreover, the plunger is streamlined, the sides thereof tapering inwardly at substantially the same angle as the reverse taper 35 of the venturi.

Cooperating with the fuel nozzle 21 is a metering pin 27, see Figs. 1 and 8, this pin together with the fuel orifice providing means for metering the charge of fuel to the engine. In the 40 present instance this metering pin is carried by the throttle valve 25, and has a cylindrical portion 27a extending freely through a central opening or duct 28 in the head of the plunger 25. This opening is undercut to receive the head 27b 45 of the pin. It will be seen that a fuel passage is provided past the portion 27a of the metering pin and this communicates with a duct 29 leading into the intake passage, thereby permitting sufficient air and fuel to flow through the throttle 50 valve, when closed, in order to idle the engine. The metering pin also is formed with a tapered valve portion 27c below the fuel orifice or inlet 21b, which valve portion is effective to close off the inlet upon elevating the metering pin when 55 the throttle valve is in its closed position.

The metering pin is supported on the upper end of a piston 30 movable within a piston chamber 31 in the plunger 25. The piston is chambered to receive a light compression spring 60 32 held in place by a plug member 33 pinned at 34 to the end of the plunger. The piston chamber at its lower end communicates with the intake passage through a port 35 in the member 33. Hence the piston 30 at one side is subject 65 to atmospheric pressure and at its opposite side is subject to the pressure prevailing at the engine side of the throttle valve, which in the present instance is the static pressure in the intake manifold.

70 The member 33 has a socket to receive a ball 36 formed on one end of a lever 37, the latter being fulcrumed through a ball and socket joint 38 carried by a boss 39. The opposite end 40 of the lever 37 is fastened by a pivot pin 41 between 75 the forked ends 42 of a tubular plunger 43. This

plunger or piston has a reduced portion adapted to slide within a cylinder 44 pinned at 45 to a bracket 46 extending from the sleeve 14. The piston 43 is open to atmosphere at its lower end and on its upper end there is seated a vacuum valve 47 provided with a depending guide stem 48 extending into the bore of the piston. Surrounding the piston and confined between flanges on the piston and the cylinder 44 is a relatively light compression spring 49. The construction provides an air dash pot, so that the upward movement of the piston 43 is resisted by the compression of air in the closed pocket above the piston. This movement also compresses the spring 49. The piston will move freely in the opposite direction under the influence of the spring 49 since the valve 47 will lift from its seat equalizing the pressure at opposite sides thereof.

The varying positions of the throttle valve 25 are controlled by means of a throttle lever 50 pivoted at its upper end at 51 to the conduit or casing 10. Connected to the lower end of the lever 50 is a rod 52 through the medium of which the lever may be manually operated by means of the usual foot pedal on the floor of the 25 car, or in any other suitable manner. Intermediate its ends the lever has a projecting stud 53 overlying the end 40 of the lever 37. The latter may be adjusted as to its lower limit of movement by means of an adjusting screw 54 extending through a tapped hole in a bracket 55.

In the present instance a manually controlled adjustment of the metering means is provided so as to vary the fuel flow at the nozzle orifice, particularly where it is desirable to enrich the mixture upon starting the engine. The casing 10 has a boss 56 in a vertical bore of which is located an adjusting screw 57. The latter is adjusted vertically by means of a knurled nut 58. The upper end of the screw engages a projecting lug 59 on the sleeve 14. Thus by turning the nut 58 the sleeve and hence the nozzle 21 may be raised or lowered so as to adjust the relative positions of the nozzle and metering pin. Pivoted to the 45 shank of the screw 57 by a pin 60 is a cam lever 61 having a cam portion 61a adapted to rest against the under surface of the lug 59. A rod or link 62 is connected to the lever and may be 50 manually operated from the dash or steering wheel to raise the sleeve 14 as indicated in dotted lines in Fig. 3 so as to adjust the fuel nozzle relative to the metering pin. This adjustment by means of cam lever 61 is resisted by a return spring 63 surrounding a stem 64 constituting an 55 extension of the screw 57. The lug 59 slides freely on the stem and the spring 63 is confined between this lug and an adjusting nut 65 on the end of the stem.

Referring particularly to Figures 8 and 9, the 60 metering pin in the present instance is constructed so as to vary the fuel flow through the metering passage 21a, and hence through the fuel orifice 21b, in accordance with engine requirements, and this construction is such as to produce any desired power curve. For the purposes of illustration, in the present instance the metering pin has successive sections of different construction to produce substantially the power curve plotted in Fig. 9, comprising a tapered 70 portion 21d for progressively increasing the fuel charge up to approximately thirty miles per hour, a straight section 21e of uniform diameter for maintaining a constant fuel flow up to approximately fifty miles per hour, and a tapered 75

section 27 for increasing the fuel charge at higher speeds. The section 27 of the metering pin provides the required enriching of the mixture at the higher ranges on account of the wind drag or resistance which varies in proportion to the effective area of the vehicle and the square of the velocity. The construction of the metering pin will, of course, vary in accordance with the engine requirements and may be determined by the power curve obtained by dynamometer tests. Hence the metering device can be designed for any desired power curve.

Referring to Figures 5 to 7 inclusive, the embodiment therein illustrated is substantially the same in construction as that above described except for slight variations in design and the following features. The lever end 40 is pivoted on a pin 41 between the forked extensions 66 of a member 61 threaded into the lower end of a thimble 68 having a stem 69 extending freely through a hole in a lug 71 extending from the sleeve 14. This lug forms a thimble to confine one end of a spring 72, the opposite end of which is confined by the thimble 68. By turning the slotted head 70 the member 68 may be adjusted relative to the member 61, thereby raising the sleeve 14 and the nozzle 21.

An arm 73 has an offset portion at one end which is connected with the end 40 of the lever 37. The other end of the arm is provided with an offset portion 73a which projects through a slot 74 formed in a foot throttle-operated lever 75. The lever 75 is pivotally mounted upon a fixed shaft or support 76 carried by the conduit 10, and is connected with the usual accelerator pedal by a rod or link 77. A lever 78 is also pivotally mounted upon the shaft 76 and is connected by a rod or link 79 with the usual hand throttle (not shown). Referring to Figure 6, when the accelerator pedal is depressed, the lever 75 is moved from its full line position to its dotted line position, thereby releasing the throttle valve 25 to permit it to be actuated by engine suction. On the other hand, however, when the hand throttle is actuated, the lever 78 is shifted and by reason of the lever engaging the offset 73a, the arm 73 is moved, and through its connections with the throttle valve, retracts or depresses said valve, thereby permitting the metering pin 27 to drop and enrich the mixture. In this respect, it will be noted that the lever 78 functions as a choke. Whenever the lever 75 is moved in the opposite direction (toward the right, Fig. 6) it functions to positively close the throttle valve. While either of the levers 50 (Fig. 2) or 75 (Fig. 6), when moved toward the right, close the throttle valve, it is to be noted that when they are moved in the opposite direction they do not move the throttle valve, but simply release the valve so that it is free to be opened by engine suction. Even though the foot pedal (accelerator) were suddenly depressed to a full open position, the only function of the levers 50 or 75 is to release the throttle valve. Such movement of the foot pedal does not affect the position of said throttle valve. For this reason, therefore, the engine cannot be flooded by any action of the levers 50 or 75, it being understood that the throttle valve opens only progressively as the engine suction increases.

In Figure 5, I have shown means for adjusting the relative fixed positions of the nozzle 21 and the metering pin 27. In the present embodiment, the conduit 10 is provided with an offset well or socket portion 80, and the slidable sleeve 14 with a lug 82 which projects into the socket and has

a loose sliding fit therein. A screw 83 extends through a hole in the lug and is threaded into the base of the socket. A compression spring 84, located within the socket, surrounds the shank of the screw and its ends engage the lug and the socket. When an adjustment is desirable, this can be effected by adjusting the screw 83 to raise the nozzle relative to the metering pin.

It will be noted that the throttle valve or plunger is preferably integrally chambered to receive a piston which is actuated by a light spring. This piston bears against the lower end or head of the metering pin which head is located in a counter bore in the valve and controls a port through the valve for the fuel. At idling speed there is a considerable depression at the lower side of the throttle i. e. the pressure is much less at the engine side than at the atmospheric side. Hence, the piston will be withdrawn and will open the fuel port. On the other hand at high speed where the pressure tends to equalize at opposite sides of the throttle valve, which is open at this time, the spring is sufficiently strong to move the piston upwardly and close the fuel port in the throttle valve, thereby moving the metering pin and effecting a leaning out of the mixture which is desirable at high speeds. When the throttle valve is closed and the engine stopped the spring 32 will move the metering pin so as to cause its valve to close the fuel orifice 21b.

It will also be noted, among other features, that the present invention provides a carburetor having a throttle valve adapted to be opened solely by differences in pressures in the intake passage, and also a single fuel nozzle and metering device for metering the fuel flowing through the nozzle, and in which the movement of the throttle to control the effective area of the intake passage adjacent the throttle is proportionate to the variation in engine suction whereas the control of the fuel flow by the metering means is independent of the engine suction and may be predetermined to produce any desired power curve.

In the present illustration of the invention I have preferred to combine the various novel features in connection with a down draft carburetor in which the fuel is delivered to the fuel nozzle by means of a fuel pump operated from the engine. An improved fuel feed to the nozzle orifice is produced by virtue of the present utilization of a fuel pump and a downwardly directed fuel nozzle, and a positive fuel charge is always ensured on account of the head of fuel formed under pressure above the fuel pipe inlet in a closed air pocket.

It will be understood that the invention is not limited to the foregoing type of carburetor nor to an arrangement requiring the use of a fuel pump. Moreover, although it is preferred to employ a vacuum operated throttle valve in the form of a stream lined plunger, the invention is not restricted to this construction, as a butterfly valve of the balanced or unbalanced kind might be utilized. Although the valve is described as opening under engine suction, it is understood that this includes any differences in pressures effective in the intake to influence the valve and resulting either from the engine operation directly or indirectly, as for example the impact action of the mixture on the throttle valve due to the kinetic energy of the air or air and fuel mixture, or pressure effects resulting from the use of a super-charger. It is understood that in describing the throttle valve as actuated by engine suction or vacuum or the like it is intended to comprehend

within such description a partly or wholly supercharged engine.

I claim:

1. A carburetor having a mixture passage, a fuel conduit, an idling speed valve adapted to close the fuel conduit, a main valve adapted to close the mixture passage and located at the engine side of said conduit, both of said valves being independently opened and as a result of suction effects induced by operation of the engine, and fuel metering means associated with said fuel conduit and movable to vary the fuel supply by the movement of said main valve.

2. A carburetor having a mixture passage, a fuel conduit having an orifice, a throttle valve in said passage at the engine side of said orifice and adapted to be opened as a result of suction effects induced at predetermined operating speeds of the engine and adapted to close said passage at predetermined low speed of the engine, fuel metering means associated with said orifice and movable to vary the fuel supply by the movement of said throttle valve, and vacuum operated means for opening said orifice when said throttle valve is closed and movable independently of the latter.

3. A carburetor comprising a casing having an intake passage provided with an air inlet and a fuel inlet, a throttle valve in said passage at the engine side of said inlets and adapted to close the passage at predetermined speed of the engine, said valve having a lateral passage therein for permitting the flow of fuel and air past the valve when the latter is closed and including means for closing the fuel inlet when the engine is not operating.

4. A carburetor comprising a casing having an intake passage provided with an air inlet and a fuel inlet, a throttle valve movably axially in said passage at the engine side of said inlets and adapted to close the passage at predetermined speed of the engine, said valve having means for permitting the flow of fuel and air past the valve when the latter is in position to close said passage, and a vacuum controlled device for closing the fuel inlet when the engine is not operating.

5. A carburetor comprising a casing having an intake passage provided with an air inlet and a fuel inlet, a throttle valve movable axially in said passage at the engine side of said inlets and adapted to close the passage at predetermined speed of the engine, said valve having means for permitting the flow of fuel and air past the valve when the latter is in position to close said passage, and a vacuum controlled device carried by said throttle valve for closing the fuel inlet when the engine is not operating.

6. A carburetor comprising a casing having an intake passage provided with an air inlet and a Venturi constriction, a throttle valve cooperating with said venturi, a fuel nozzle, and means movable independently of said throttle valve and controlled by the operation of the engine for opening said fuel nozzle when the throttle valve is in position to close said passage.

7. A carburetor comprising a casing having an intake passage provided with an air outlet and a Venturi constriction, a stream lined throttle valve cooperating with said venturi, a fuel nozzle, and metering means movable independently of said throttle valve and controlled by the operation of the engine for opening said fuel nozzle when the throttle valve is in position to close said passage.

8. In a carburetor, a casing comprising an ad-

justable portion, a fuel nozzle carried thereby, a metering pin in said nozzle, and manually operated means for adjusting said casing portion and nozzle relative to said metering pin.

9. A carburetor having an intake passage provided with a venturi, a movable plunger located in said venturi and operated by engine suction to control the effective opening in the passage adjacent said venturi, cushioning means for said plunger located outside said intake passage, means interconnecting said plunger and said cushioning means, a source of fuel supply, metering means for the fuel including relatively movable parts, the movable part of the metering means being moved as a result of the engine suction but said metering means being constructed to control the fuel independently of the engine suction.

10. A carburetor having an intake passage, a throttle valve adapted to be opened solely by differences in pressure in said passage, a fuel nozzle, a metering device movable with said valve and having means for varying the fuel flow through the nozzle independently of the variations in pressure resulting from the engine operation, and means operative to close said valve but ineffective to open the same.

11. A down-draft carburetor comprising a casing having an inlet passage provided with an air inlet and a fuel inlet, a vacuum operated throttle valve in said passage for controlling the flow of air from said air inlet, and a vacuum operated device having a valve for closing said fuel inlet when the engine is not operating.

12. A carburetor comprising a casing provided with an intake passage having air and fuel inlets and a venturi, a throttle valve movable axially in the passage and cooperating with said venturi to open and substantially close the passage, said valve being at the engine side of said inlets and being actuated by pressure differences at opposite sides thereof, and mechanism extending exteriorly of the casing for closing said valve but ineffective to open the same.

13. A carburetor comprising a casing provided with an intake passage having air and fuel inlets and a venturi, a stream-lined throttle valve movable axially in the passage and cooperating with said venturi to open and substantially close the passage, said valve being at the engine side of said inlets and being actuated by pressure differences at opposite sides thereof, and spring controlled mechanism extending exteriorly of the casing for closing said valve but ineffective to open the same.

14. A carburetor comprising a casing having an intake passage provided with air and fuel inlets and a Venturi constriction at the engine side of said inlets, a throttle valve movable axially substantially within said constriction at the engine side of said inlets and adapted to be opened by differences in pressure acting thereon, and manually operated means for closing said valve.

15. A carburetor comprising a casing having an intake passage provided with air and fuel inlets and a Venturi constriction at the engine side of said inlets, a throttle valve movable axially substantially within said constriction at the engine side of said inlets and adapted to be opened by differences in pressure acting thereon, and manually operated means for controlling the position of said valve but ineffective to open the same, said valve having means remote from the engine and movable therewith to meter the fuel.
